STEREOPHONIC RADIO AND PHONOGRAPH CABINET WITH SLIDABLY REMOVABLE LOUDSPEAKER UNITS

Stanley A. Sherno, Grandview Road,
Ebensburg, Pa. 15931

Filed Feb. 24, 1967, Ser. No. 5,940

Term of patent 14 years

(Cl. D56—4)

FIG. 1.

FIG. 2.

FIG. 3.

FIG. 4.

FIG. 5.

FIG. 6.

FIG. 1 is a perspective view from above and the front of a stereophonic radio and phonograph cabinet with slidably removable loudspeaker units, showing my new design;

FIG. 2 is a perspective view from above and the rear;

FIG. 3 is a front elevation;

FIG. 4 is an end elevation, both ends being similar in appearance;

FIG. 5 is an end view similar to FIG. 4 but with the cover lifted; and

FIG. 6 is a perspective view similar to FIG. 1 but with the cabinet opened and the two end loudspeaker units slidably skewed to face sidewardly in their retaining channels.

The bottom surface is flat and rectangular supported on duplicate pairs of legs as shown in FIGS. 3 and 4.

The turntable and radio phonograph control knobs shown in FIG. 6 are for illustrative purposes only.

I claim:

The ornamental design for a stereophonic radio and phonograph cabinet with slidably removable loudspeaker units, as shown and described.
